SHOE SEWING MACHINE

Miloslav Muc, Slatinice, near Olomouc, Czechoslovakia, assignor to Bata, narodni podnik, Zlin, Czechoslovakia

Application March 14, 1947, Serial No. 734,754
In Germany December 1, 1942

Section 1, Public Law 690, August 8, 1946
Patent expires December 1, 1962

10 Claims. (Cl. 112—46)

1

This invention relates to shoe sewing machines and in particular to machines for attaching the sole to the upper leather by means of a decorative welt or a false welt sewn around the edge of the sole.

One of the problems encountered in sewing on the welt which is usually fed from a large roll is to cut it off at the proper place so that when the sole has been sewn around the entire periphery, the two ends of the welt will meet exactly.

The prior methods and machinery for cutting the welt have not been completely satisfactory. One technique which has been used is to control the operation of the cutting device in accordance with an impulse or control signal from the return of the beginning end of the welt already sewn on to the sewing location. In one device of this type a special feeler is provided that is arranged independent of the guide member for the welt strip and upon traveling up against the beginning of the welt releases the cutting knife, by whose mechanically instigated movement against the guide member of the welt, the latter is cut off.

This type of device has however many disadvantages. One drawback resides in the fact that the cutting knife has to be removed from its guide each time that it is sharpened. This is a very tedious operation and furthermore the knife must be readjusted into the exact position necessary for the correct cutting stroke whenever it is sharpened.

In another known automatic welt cutter of the impulse type, the cutting knife remains in a fixed position and is structurally combined with the guide member for the welt strip into one piece. However, this arrangement is also unsatisfactory for the reason that continued resharpening of the knife ultimately renders the whole guide useless and it must be replaced.

The improved method according to the present invention permits elimination of the drawbacks mentioned and also the construction of a new satisfactory device for automatic cutting-off of the welt strip and is based on the fact that by the impulse given by the traveling up on the beginning of the welt already sewed on, an automatic stroke of the guide member of the welt against an immovably mounted knife is released and thereby the welt is cut off. This process makes possible an advantageous combination of a number of actions in a single member, specifically the guide member of the welt strip itself, that acts at the same time as feeler for feeling the welt origin and for releasing the stroke device against the fixed knife and preferably likewise

2

forms a part of the feed device of the machine. The device serving for carrying on the method according to the invention therefore offers appreciable advantages over all constructions of welt cutting devices disclosed heretofore. A further advantage yielded by the invention is good visibility of the work place and convenient exchangeability of the easily accessible fixed knife, that can be easily adjusted.

10 Further advantages and features of the invention will be apparent from the following description of one constructional example in connection with the appended drawings.

Fig. 1, a view in perspective, illustrates the 15 whole apparatus of a cutting device for a duplex machine operating according to the invention.

Fig. 2, likewise a perspective view, shows the 20 appertaining control mechanism on a larger scale.

Fig. 3 is a view in elevation of the working 25 place during normal sewing.

And Fig. 4 is the same elevational view in the condition just before the cutting off of the welt.

The constituents of the sewing device carrying 30 barbed needle 1 and the awl 2 already known per se are omitted from the drawings for the 25 sake of clarity; these drive members can be constructed and arranged in any suitable way.

The needle 1 and the awl 2 describe reciprocating motions in a circular path through a slot 3 in the customary support 4 for the piece of work 4a. In the direct neighborhood of the work support 4 is located the cutting knife 5 and a foot 6 through the opening 7 of which is led the welt strip 8 taken from a receptacle that is not shown. The knife 5 is curved and adjustable, for instance anchored by means of a screw 9 in a holder 10 that is carried by a bracket 11. This bracket 11 is mounted to slide with all its constituents on a pin 12 of the fixed machine arm

13. The guide foot 6 of the welt 8 is likewise secured in a removable and adjustable manner in a guide 14 of the lower arm of a two-armed lever 15, specifically by means of a screw 16. The two-armed lever 15 is mounted so as to turn on a pin 17 of the bracket 11 already mentioned, which in addition carries a pivot 18 of the two-armed lever 19 likewise mounted to swing. To the upper arm of this lever 19 is secured a projection 20 carrying the channel cutter 21 for cutting the sole groove receiving the seam, this projection 20 likewise carrying a toothed feeder foot 22 (cf. Fig. 3) for the stitch-like advance of the piece of work. The bracket 11 is given the ordinary reciprocating movement along the pin 12 for the purpose of stitch-like advance of the piece

of work, the feeder foot 22 from above and the foot 6 from below alternately clamping and freeing the piece of work. The guide foot 6 in this connection thus performs the function usually performed by the work support in alternately clamping and releasing the piece of work for advancing the same.

The upper arm of the lever 15 carries a ball pivot 23 of the draw-bar 24, the opposite end of which is likewise hung by a ball pivot 25. This ball pivot 25 changes over into a cylindrical pin 26 (cf. Fig. 2) on which engages, on the one hand, the fork 27 of a draw-bar 28 and on the other hand a rail 29 that for instance has a U-profile and is guided so as to slide in the recess 30 of a bracket 31 mounted in a fixed fashion in the machine frame. In the lower part of the recess 30 of the bracket 31 is provided an inclined slot 32, in which roller 33 is laid and pressed by a spring 34 against the narrow side of the slot, this roller thus clamping the rail 29 in the recess 30; the release of the lock constituted by members 32, 33, 34 is accomplished by pressure on the roller 33 by means of a bolt 35 against the influence of the spring 34. This bolt 35 is governed by the projection 36 of a two-armed lever 37, that is mounted so as to turn on a pin 38 of the bracket 31 and by means of a roller 39 is actuated by a cam 40 provided on the main shaft 41 of the machine. The parts 42 and 43 of the cam track 40 correspond to the locked position of the roller 33 while the projection 44 causes the release of the lock members 32, 33 and 34.

Besides the cam 40, an additional cam 45 is provided that has a deep notch 46 and a slight projection 47. This cam 45 acts on the roller 48 of a three-armed lever 49, that can turn on a pivot 50 mounted fast in the machine frame (Fig. 1). The roller 48 is held in engagement with the cam 45 by a spring 51 hooked to the lower arm 52 of the lever 49. To the upper arm 53 of the lever 49 is secured a pivot 54 on which the draw-bar 28 with a long recess 55 is suspended. The draw-bar 28 is constantly drawn to the right by a spring 52' hooked on the one hand in the pivot pin 26 and on the other hand in the pivot pin 54, the long recess 55 furnishing play for the guide foot 6 agreeing with the thickness of the welt 8 (Figs. 3 and 4). The highest position of the guide foot 6 is determined by the striking of a bolt 73 against the end of a groove 74 in the bracket 31 (Fig. 2). In order that the lock, comprising members 32, 33 and 34 of the rail 29 can be held in the released position independent of the position of cam 40 or of its projection 44 (for reason to be explained later), an angle lever 57 furnished with a pawl 56 is placed in front of the bolt 35 or the projection 36 of the lever 37, this angle lever being capable of turning on the pin 58 of a supporting plate 59 secured to the bracket 31. The upper arm of the angle lever 57 is provided with a fork 60 in which an adjustable bolt 61 (Fig. 1) of the draw-bar 24 engages.

In order to be able to set the cutting device entirely out of operation for any desired length of time, the lower arm of the three-armed lever 49 is provided with a stop 62 (Fig. 1) on which the pawl 63 comes to rest, this preventing the lever 49 from swinging out under the influence of the spring 51. The pawl 63 is mounted so that it can turn on a pivot 64 mounted in the machine frame and is shifted by means of a linkage system comprising members 65, 66, 67, 68, 69 and 70 by a bowed member 71, the latter being controlled for instance by a knee of the operator serving the

machine. This entire lever system is under the influence of a spring 72 so that as long as no force is exerted on the knee-bow member 71 from outside, the pawl 63 is in engagement with the stop 62 and the cutting device is thus out of operation.

The method of operation of the device described is as follows:

During sewing, the cam shaft 41 receives a turning motion in the direction S₁ (Fig. 1) whereby the needle 1 and the awl 2 describe the normal working movements and sew the welt strip 8 to the upper part and the sole 4a of the shoe being made. The lateral movement of the projection 20 carrying the feeder foot 22 necessary for this and of the foot 6 takes place with the help of the bracket 11, to which this movement is transmitted in the ordinary way from the cam shaft through a device not shown.

From the beginning of the sewing operation on a piece of work up to just before completion of the sewing over the entire periphery of the shoe sole 4a, the cutting device of the welt strip 8 remains set out of operation since the pawl 63 holds the stop 62 fast, as already described earlier. When the sewing operation has almost reached the end, the operator presses the knee bow 71 to the right (according to Fig. 1) so that with the aid of the lever system already described, the pawl 63 is brought out of engagement with the stop 62 and then all the requirements for the cutting off of the welt at the required moment are met, i. e. upon traveling up of the foot 6 on the welt origin already sewed on.

The cutting operation proceeds as follows:

Upon each rotation of the cam shaft 41, that corresponds to a stitch, the projection 44 of the cam 40 effects a release of the lock (32, 33, 34) of the rail 29. This releasing action is obtained by upward movement of roller 39, which causes the projection 36 of the two-armed lever 37 to be forced in the direction S₃ (Fig. 2), thus causing the bolt 35 to be pressed against the locking roller 33. The latter is thus pushed back against the influence of the spring 34 and the rail 29 is freed. If at this moment, the foot 6 however is not pushed down at the same time, i. e. the foot assumes the position shown in Fig. 3, the projection 36 of the lever 37 goes right back to its original position after the projection 44 of the cam 40 has turned past and the roller 33 again blocks the sliding movement of the rail 29 to the left. Thus in this case, even with released pawl 63, the roller 48 of the lever 49 cannot follow the cam track 45 and the recess 46 since the lever 49 cannot swing out, because of the firmly locked rail 29. The same operation is repeated at each stitch as long as the foot 6 slides along the surface of the piece of work still not covered by the welt strip 8, as according to Fig. 3, during the reverse movements of the feeder device.

Just before the completion of the sewing operation, the moment is finally reached when the foot 6 rides up on the beginning of the welt 8 already sewed on; Fig. 4 shows this moment. Since the cam position is adjusted so that the foot 6 describes its reverse movement in relation to the piece of work at a time in which the rail 29 is just liberated under the influence of the projection 44 of the cam 40, then upon the depressing of the foot 6, due to its traveling up on the beginning of the welt 8, the draw-bar 24 with the rail 29 and the draw-bar 28 are pushed to the left (Fig. 1) against the pull of the spring 51, the long recess 55 of the draw-bar 28 sliding on the pin 54 of the lever 53 and the pin 61 of

the draw-bar 24 shifting the fork 60 into the position shown in Fig. 2 by solid lines. In this position the pawl 56 rests against the projection 36 that has just taken up its position releasing the lock (32, 33, 34) of the rail 29. Meanwhile the foot 6 has traveled completely up on the beginning of the welt, the pivot 61 and with it likewise the fork 60 remains in the position shown in Fig. 2, even when the projection 44 of the cam 40 has run past the roller 39 so that the latter retains its raised position and goes out of contact with the cam 40.

Only when this condition of free mobility of the rail 29 and of the parts belonging to it is attained can the roller 49 of the three-armed lever 49 follow the cam track 46, so that the lever 49, together with the rod system 28, 24, swings out to the left and the guide foot 6 secured to the two-armed lever 15 can be shifted downwards into the position shown by dotted lines in Fig. 4. The cutting-off of the welt strip 8 occurs during this swinging, since it is moved down forcibly by the foot against the edge of the knife 5. The moment of cutting off is thereby adjusted exactly to the welt beginning already sewed on. The operator can then finish sewing the remaining stitches and after lifting off the feeder foot 28 can remove the piece of work from the machine.

The foot 6, after the welt strip 8 is cut off, is lifted again by the cam 45, so that the draw bars 24 and 28 go back to their original positions, the pin 61 of the pull rod 24 putting back the fork 60 likewise into the original position shown by dotted lines in Fig. 2. The projection 36 is thus freed and can be shifted again to the left until the roller 39 of the lever 37 rests on the cam 40 and the lock 32, 33, 34 goes into operation as soon as the roller 39 leaves the projection 44 of the cam 40. The working operation is then completed and can be repeated in the same way with the next piece of work.

A main feature of the device according to the invention is to be found in the fact that guide foot 6 does a whole series of tasks; it serves as a guide member for the welt strips, as an aid to the feed device of the duplex machine and finally as a feeler for feeling the beginning of the welt and for releasing the cutting device.

In conclusion, it will now be evident that the novel method of cutting off the welt according to the invention is predicated upon an impulse instigated by the return of the beginning end of the welt which results in a forced stroke of the guide member 6 for the welt 8 against a fixed knife 5. Furthermore, it will be understood that while the illustrated machine for carrying out the novel method of cutting off the welt is to be preferred, changes in the construction of the machine parts as well as substantially different machine arrangements may be effected without departing from the spirit and scope of the invention.

1. In a sewing machine for use in the manufacture of shoes, the combination with stitch forming mechanism acting to secure a welt progressively around a shoe, of a welt guide for directing the welt into proper position on the shoe upper in advance of the sewing point, means supporting the welt guide to allow an initial motion thereof upon contact with the return of the beginning end of the sewn on welt, a stationary knife positioned adjacent the guide, and means conditioned in response to the initial motion of said guide for effecting an additional motion

thereof to bring the welt against and be cut by said knife.

2. In a sewing machine for use in the manufacture of shoes, the combination with stitch forming mechanism acting to secure a welt progressively around a shoe, of a welt guide for directing the welt into proper position on the shoe upper in advance of the sewing point, means supporting said welt guide to permit an initial downward motion thereof upon contact with the return of the beginning end of the sewn on welt, a stationary knife positioned below said welt, and means conditioned in response to the initial motion of said guide for effecting a further downward motion thereof to bring the welt against and be cut by said knife.

3. A sewing machine as defined in claim 2 and further including means locking said last named means in an inoperative position and a manually actuated device for releasing said locking means.

4. In a sewing machine for use in the manufacture of shoes, the combination with stitch forming apparatus to secure a welt progressively around a shoe, and a reciprocating feed device for feeding the shoe past the sewing point, of a welt guide for directing the welt into proper position on the shoe upper in advance of the sewing point, said welt guide also constituting a feeder foot of the feed device, means supporting said welt guide to allow an initial downward motion thereof upon contact with the return of the beginning end of the sewn on portion of the welt, a stationary knife positioned below said welt, mechanism conditioned by the initial motion of said guide for effecting further downward motion thereof to bring the welt against and be cut by said knife, and means controlled in timed relation with operation of said feed device for determining the operating moment of said mechanism.

5. In a sewing machine for use in the manufacture of shoes, the combination with stitch forming apparatus to secure a welt progressively around a shoe and a reciprocating feed device for feeding the shoe past the sewing point, of a welt guide for directing the welt into proper position on the shoe upper in advance of the sewing point, said welt guide also constituting a feeder foot of the feed device, means supporting said welt guide to effect a downward motion thereof upon contact with the return of the beginning point of the sewn on portion of the welt, a stationary knife positioned below said welt, mechanism conditioned by initial motion of said guide for effecting further motion thereof to bring the welt against and be cut by said knife, a manually actuated device for rendering said mechanism incapable of operation, and means controlled in timed relation with the operation of said feed device for also holding said mechanism inoperative except when said welt guide occupies its rearmost position in the feed stroke.

6. A sewing machine as defined in claim 5 wherein said welt guide is supported by a pivoted lever and said mechanism for depressing said welt guide is constituted by a spring loaded lever system connected to said pivoted lever.

7. In a sewing machine for use in the manufacture of shoes, the combination with a stitch forming apparatus to secure a welt progressively around a shoe and a reciprocating feed device for feeding the shoe past the sewing point, of a welt guide for directing the welt into proper position on the shoe upper in advance of the

sewing point, said welt guide also constituting a feeder foot of the feed device, means supporting said welt guide to allow an initial depression thereof upon contact with the return of the beginning point of the sewn on portion of the welt, a stationary knife positioned below said welt, a spring loaded mechanism for further depressing said welt guide and welt subsequent to the initial movement thereof to bring the welt against and be cut off by said knife, a device alternately locking and unlocking said mechanism as the sewing progresses, means actuated in response to an initial depression of said guide to secure said locking device in its unlocked position, and means controlled in timed relation with the operation of said feed device for determining the exact operating moment of said mechanism.

8. A sewing machine as defined in claim 7 and further including a manually operated release for said spring loaded mechanism.

9. A sewing machine as defined in claim 7 wherein the last said means is comprised of a cam having a depression in the cam track, said cam being driven by a cam shaft of the sewing machine, a cam roller mounted on one arm of

15 a pivoted lever connected in the spring loaded mechanism, and the latter is freed for operation when said roller rides down into the depression in the cam track.

10. A sewing machine as defined in claim 7 wherein said mechanism includes a rail reciprocating in a slotted portion of a stationary member of the sewing machine, and said rail is alternately locked and unlocked relative to said slot by means including a cam and cam roller, the cam being driven by a cam shaft of the machine in such manner that the rail is locked and unlocked once for each stitch taken by the machine.
